(57) **CLAIM**

The ornamental design for a bottle, as shown and described.

DESCRIPTION

FIG. 1 is a perspective view of the bottle;
FIG. 2 is a front elevational view of the bottle, in which the
opposing rear elevational view, the right side view and the
left side view are identical to the front elevational view
shown;
FIG. 3 is a top plan view of the bottle; and,
FIG. 4 is a bottom plan view of the bottle.

The portion of the bottle shown in broken line forms no part
of the claimed design.
